UNITED STATES PATENT OFFICE.

LOUIS C. BONNOT, OF LOUISVILLE, AND WILLIAM M. BARKER, OF CANTON, OHIO, AS
SIGNORS TO THE BONNOT COMPANY, OF CANTON, OHIO, A CORPORATION OF OHIO.

PULVERIZING MILL.

Application filed November 4, 1925. Serial No. 66,855.

The invention relates to a rotary drum grinding or pulverizing mill partly filled with balls or other grinding media for the dry fine pulverizing of material such for 5 instance as coal, limestone and the like, which is fed into one end of the drum; and more particularly to the separation of the finely pulverized material which is carried out of the drum by an induced air current 10 or suction created by a centrifugal exhaust separator.

The object of the improvement is to provide a machine of this character having means for preventing the grinding media 15 from being thrown or drawn into the fan of the separator and damaging the same, and provided with an exhaust cone in the discharge end of the mill, leading to the separator, and having spiral fins and a receding, concave, peripheral flange, for plowing or deflecting and repelling the balls and coarse material away from the cone and continually forming a furrow in the ball mass adjacent to the peripheral flange for receiving 20 among the balls any coarse material which is by-passed from the exhaust separator and returned through the nozzle in the cone to the mill. Also, to provide means for returning to the drum any coarse material 25 which may be thrown or drawn into the cone; to provide for a decreased suction at the exhaust side of the drum and an increased suction in the exhaust end of the cone by means of the difference in area of 30 the opposite ends of the cone, in order to carry only the finely pulverized portions of material into the inlet end of the cone; the increased velocity, at the outlet end of the cone serving to quickly exhaust the fine material 35 through the exhaust separator and providing sufficient velocity to prevent the fine material from settling in the passages and obstructing the same; the decreased velocity at the exhaust side of the drum, however, being sufficient to carry the finely pulverized material out of the drum and prevent the same from settling in the mill and cushioning the balls.

And finally, to provide a by-pass and 40 centrifugal separator at the outlet side of the exhaust, to create a counterdraft through the nozzle into the cone for returning to the drum oversized material segregated by the exhaust separator as well as to clear the 45 cone of any coarse material which may be

deposited therein by the grinding action; thus making a complete separation of the finely pulverized material and eliminating the necessity of using an independent cycle separator or other separating apparatus. 60

The improved mill is well adapted for pulverizing small lump or slack coal for use in furnaces or powdered fuel feeding systems, but it should be understood that it is equally well adapted for pulverizing other coarse or 65 granular materials.

The present improvement also contemplates the elimination of the usual axial tube or center pipe extending into and sometimes through the drum, in air swept mills, the 70 raw material being fed preferably through an inlet cone and through an axial opening into one end of the drum, a perforate baffle plate in the center of this opening breaking the suction through the axial center of the 75 drum. The drum is preferably supported upon flanged rollers journaled upon a shaft, and is provided with a ring gear meshing with a driving pinion carried in an adjustable bearing. 80

An embodiment of the improved pulverizing mill is illustrated in the accompanying drawings, forming part thereof, in which—

Figure 1 is an axial section through the improved mill;

Fig. 2, a section on line 2—2, Figure 1;

Fig. 3, a section on line 3—3 Figure 1;

Fig. 4, a vertical section through the centrifugal exhaust separator, and

Fig. 5, a fragmentary section on the line 90 5—5, Figure 1, showing the action of the spiral fins and counter-current from the exhaust separator.

Similar numerals of reference indicate corresponding parts. 95

The grinding drum 10 is mounted upon the flanged rollers 11 which are journaled upon the shaft 12, and is arranged to be driven through the ring gear 13 carried upon the drum, and the driving pinion 14, meshing therewith, and journaled upon brackets 15 arranged to be adjustably mounted upon the supporting base 16 as by the bolts 17 and adjusting screw 18.

The inlet end of the drum may be provided 105 with the axial feed cone 19, and a perforate disk 20 is mounted in the opening of the base thereof and connected to the end wall of the cone as by radial wings 20' and bolts 21.

The periphery of this disk is spaced from the 110

periphery of the feed opening of the drum, as shown at 22, permitting the greater part of the material to be fed around and beneath the disk into the drum, while the perforate 6 disk permits a portion of the air to be drawn axially through the drum, breaking the direct axial draft from the feed inlet to the exhaust cone and preventing any but the very finest particles of the material from being carried directly into the outlet or discharge cone of the drum.

The discharge or exhaust cone 23 is connected to the discharge end of the drum as by the peripheral flange 24 and bolts 25. 15 This discharge cone may be provided with a lining formed of segmental sections 26 provided with the spiral fins 27, the inner ends of which are spaced from each other near the small end of the cone and the outer ends of 20 the fins preferably extend over the angles of the peripheral rim flange 28 and terminate in the receding annular groove 29 formed in said flange.

The discharge cone exhausts into the discharge neck 30, which is connected to the inlet opening of the centrifugal fan chamber 31 of the exhaust separator and is preferably provided with an angularly disposed screen 32, of substantially coarse mesh, to 25 deflect any balls which may be thrown into the same.

An exhaust impeller 31' is located within the fan casing 31 and is arranged to be rotated as by the motor 33. An outlet pipe 34 35 communicates with the fan casing for carrying away the finely pulverized material which is exhausted from the drum.

A by-pass 35 communicates with the outlet side of the fan casing and extends beneath the pan 36 in the discharge neck 30, 40 said pan having a deflecting flange 37 substantially parallel with the bottom wall of the discharge cone and forming a nozzle arranged to project a blast of air inward along 45 the bottom wall of the cone.

This centrifugal-fan by-pass construction has three functions; first, it acts as a centrifugal separator, segregating the over size material which is drawn into the exhaust 50 separator and providing a passage for the return of the same to the mill for regrinding; second, it sets up a counter-current of air from the end of the nozzle, through the exhaust cone, that tends to prevent the coarse 55 material from being drawn into the cone; and third, it continually cleans the walls of the cone from any coarse material which may be deposited thereon.

As a consequence the capacity of the mill 60 is greatly increased because sufficient suction is maintained to withdraw all of the fine material as soon as the same is pulverized to the proper mesh, while the greater portion of the coarser material is repelled from entering the exhaust cone, and any small per-

centage of the coarse material which is carried into the exhaust cone by the gradually increasing velocity of the exhaust air current is automatically separated and returned to the mill, by the exhaust separator, for further grinding, which eliminates the necessity of a cyclone separator or other independent separating apparatus.

With this construction, the material to be pulverized is passed from the inlet cone, 75 around the periphery of the perforate plate 20, and only the very finest material is carried through the perforations and axially through the drum to the exhaust cone.

The material is thrown around in the 80 drum with the balls 38 by centrifugal action, pulverizing the material, and only the very finest particles thereof are exhausted through the fan, as the area of the large end of the discharge cone is several times greater than the area of the discharge end thereof, providing a comparatively low velocity of suction at the large end of the cone, which will pick up only the very finest particles of material, and a greatly accelerated velocity of 85 suction at the discharge end of the cone, quickly clearing the same of the fine particles of material.

Thus only the fine material will be exhausted into the fan where a further separation is attained, and the material is discharged into connecting bins with such uniformity as not to require any grading or 90 classifying.

The balls and coarse material are repelled 100 from entering the large mouth of the discharge cone and are prevented from riding up upon the walls thereof by means of the annular groove 29 and the spiral fins 27, and coarse material is further repelled and 105 prevented from being carried up along the walls of the cone by means of the counter air current above described, while any balls which may be thrown into the exhaust neck will strike the screen 32 and be returned to 110 the drum by the above described means.

The means for preventing grinding balls from entering the fan and the use of a perforate disk in the feed opening, which are illustrated and described but not claimed 115 herein, are made the subject matter of parent application, Serial No. 47,039, filed July 30, 1925, by these applicants.

We claim:

1. A material pulverizing mill including a 120 rotary drum with grinding media therein, a feed opening in one end of the drum and an axial discharge cone flared inward forming an outlet opening extending from the other end of the drum, the mouth formed by the 125 larger end of the cone being substantially unobstructed, means impelling a current of air through the drum from the inlet to the outlet thereof, and peripheral means repelling the entrance of grinding media and coarse 130

material into the mouth of the discharge cone.

2. A material pulverizing mill including a rotary drum with grinding media therein, a feed opening in one end of the drum and an axial discharge cone flared inward forming an outlet opening extending from the other end of the drum, means impelling a current of air through the drum from the inlet to the outlet thereof, and means repelling the entrance of grinding media and coarse material into the mouth of the discharge cone, said means including an outwardly flared rim flange connecting the large end of the discharge cone with the peripheral portion of the drum.

3. A material pulverizing mill including a rotary drum with grinding media therein, a feed opening in one end of the drum and an axial discharge cone flared inward forming an outlet opening extending from the other end of the drum, said cone having a rim flange extending to the periphery of the drum, means impelling a current of air through the drum from the inlet to the outlet thereof, and spiral fins on the interior of the discharge cone extending over the rim flange thereof.

4. A material pulverizing mill including a rotary drum with grinding media therein, a feed opening in one end of the drum and an axial discharge cone flared inward forming an outlet opening extending from the other end of the drum, means impelling a current of air through the drum from the inlet to the outlet thereof, means repelling the entrance of grinding media and coarse material into the mouth of the discharge cone, said means including an outwardly flared rim flange connecting the large end of the discharge cone with the peripheral portion of the drum, and spiral fins on the interior of the discharge cone extending over the rim flange thereof.

5. A material pulverizing mill including a rotary drum with grinding media therein, a feed opening in one end of the drum and an axial discharge cone flared inward forming an outlet opening extending from the

other end of the drum, means impelling a current of air through the drum from the inlet to the outlet thereof, means repelling the entrance of grinding media and coarse material into the mouth of the discharge cone, and a nozzle in the discharge end of the cone projecting a current of air inwardly along the bottom wall thereof.

6. A pulverizing mill including a rotary drum with grinding media therein, a discharge cone flared inward at the discharge end of the drum and having a peripheral, angularly flared rim flange provided with an annular groove for deflecting the grinding media away from the entrance to the cone.

7. A pulverizing mill including a rotary drum with grinding media therein, a discharge cone flared inward at the discharge end of the drum and having a peripheral, angularly flared rim flange provided with an annular groove, and spiral fins on the interior of the cone extending into the annular groove for deflecting the grinding media away from the entrance to the cone.

8. A pulverizing mill including a rotary drum with grinding media therein, a discharge cone flared inward at the discharge end of the drum, an exhauster separator communicating with the discharge cone, a return air discharge nozzle in the discharge end of the cone and a by-pass from the outlet side of the exhauster separator to the nozzle.

9. A pulverizing mill including a rotary drum with grinding media therein, a discharge cone flared inward at the discharge end of the drum, an exhauster separator communicating with the discharge cone, a return air discharge nozzle in the discharge end of the cone, a by-pass from the outlet side of the exhauster separator to said nozzle and a deflecting flange upon the nozzle spaced from the walls of the cone.

In testimony that we claim the above, we have hereunto subscribed our names.

LOUIS C. BONNOT.
WILLIAM M. BARKER.
